UNITED STATES PATENT OFFICE.

JAMES D. REIFSNYDER AND HENRY G. SCHWERDTLE, OF PHILADELPHIA, PENNSYLVANIA, ASSIGNEES TO STOKES & SMITH COMPANY, OF SUMMERDALE, PENNSYLVANIA, A CORPORATION OF PENNSYLVANIA.

FEEDING MECHANISM.

1,202,315.

Specification of Letters Patent. Patented Oct. 24, 1916.

Application filed February 28, 1914. Serial No. 821,665.

To all whom it may concern:

Be it known that we, JAMES D. REIFSNYDER and HENRY G. SCHWERDTLE, citizens of the United States, residing at Philadelphia, in the State of Pennsylvania, have invented new and useful Improvements in Feeding Mechanism, of which the following is a specification.

This invention relates to printing presses of the rotary type containing mechanism for successively feeding thereto sheets to be printed from the bottom of a pile of sheets, and has for one object to provide in connection with an automatic sheet feeding mechanism, including a reciprocating table supporting the sheets to be printed and a suction picker in the form of an oscillating roller, that engages the bottom sheet of the pile of sheets as it reciprocates over said 15 roller and draws the edge of said sheet away from the pile, of means connected to the rear edge of said table and extending to the suction picker roller to span the space therebetween and support the rear of the pile of 20 sheets that projects over said space, said means adapted to decrease and increase in 25 length as the table reciprocates toward and away from said suction picker.

A further object of the invention relates 30 to a separator that enters between the sheet being fed and the stack of sheets to prevent said sheet returning to the pile of sheets should it be disengaged from the suction picker, and also to direct said sheet down- 35 wardly between positively driven feed rollers by which it is drawn from the pile and advanced to the printing mechanism.

Another object of the invention relates 40 to an attachment for said separator by means of which heavy paper and cardboard are fed to the printing devices as readily as a thinner and more flexible paper.

With these and other objects in view the invention consists of the novel construction, 45 combination and arrangement of parts hereinafter described, pointed out in the claims, and illustrated in the accompanying drawings, in which—

Figure 1 is a side elevation of a portion of 50 a printing press with the invention applied thereto. Fig. 2 is a vertical longitudinal sectional view of the same. Fig. 3 is a similar view of the feed table and its carrying frame. Fig. 4 is a bottom plan view of the

parts illustrated in Fig. 3. Fig. 5 is a detail 55 sectional view, enlarged, of a portion of the feeding mechanism showing the attachment used when printing cardboard. Figs. 6 and 7 are enlarged detail views of the cardboard feed attachment. 60

In the drawing, 15 indicates the main frame of a printing press at the top of which are arranged in parallel relation a form cylinder 16, an impression cylinder 17, and a take-off frame 18, their axes lying in a common horizontal plane. A driving pulley 19 on a shaft 20 rotates a pinion 21 that engages a gear wheel 22 on one end of the form cylinder, which gear meshes with a gear wheel 23 of the same diameter on the 70 impression cylinder, and the latter gear wheel in turn drives the gear wheel 24 on the take-off frame. The impression cylinder 17 carries as usual one or more gripper fingers 25 that are opened at the proper time 75 by a fixed cam 26 and then closed to clasp the edge of the sheet to be printed against the impression cylinder. Other gripper fingers 27 on the take-off frame 18 and actuated through a fixed cam 28, receive the printed 80 sheet from the impression cylinder and carry it to a delivery table 29 when the grippers open and permit the sheet to drop on the table. In rear of the form cylinder 16 are arranged the inking rollers 30. 85

Hinged to the front of the main frame 15 near the top thereof is a swinging frame 31 having depending legs 32 pivoted at 33 to a bracket 34 projecting from the main frame upon which the frame 31 is adapted to swing 90 from its normal position overlying the impression cylinder and take-off frame, as shown in full lines in Fig. 1, to an elevated position, see dotted lines same figure. The raising and lowering of the frame 31 may 95 be performed directly by grasping it with the hands, but preferably by means of a worm 35 turning in bearings on the main frame operating a toothed segment 36 affixed to said swinging frame. 100

Upon the swinging frame 31 is mounted automatic feed mechanism which will now be described. The swinging frame 31 comprises two parallel side bars 37 secured together by suitable cross-braces, from each of 105 which bars one of the legs 32 depends. These bars 37 have each a rail 38 projecting from its inner face upon which a longitudinally

reciprocating table 39 is supported, said table having side flanges 40 that rest upon the rails 38. On the top of the table 39 are carried three vertical plates or boards 41 curved 5 outwardly at their upper ends which abut against three sides of the pile of sheets to be printed and which are adjustable on the table. These boards or plates are adjustable to the size of the sheets by securing bolts 10 42 and thumb nuts 43, the heads of the bolts engaging undercut grooves 44 in the top of the table. Bolted to the rear of the table at each side is an upwardly and backwardly inclined bracket 45 between the free ends of 15 which extends a rod 46 on which is pivoted a fourth upright board 47 that abuts against the rear side of the pile of sheets that overlies the rear edge of the table, and prevents movement of said sheets as the table reciprocates. The board is substantially fixed, but may be given a slight swinging movement on the rod 46 by means of an adjusting screw 48 on the bracket that engages an 20 arm 49 rigid with the board 47. Depending from the underside of the table 39 is a bracket 50 to which is pivoted a link 51 that is also connected to the free end of an arm 52 projecting upwardly from a shaft 53 that 25 extends crosswise of the swinging frame 31 and is pivoted in the legs 32 thereof. Preferably there are two of these arms 52 and their accompanying links 51 and brackets 50, one on each side of the machine. An arm 30 54 depends from one end of the shaft 53 and is joined at its lower end to a rod 55 that extends rearwardly to a crank-pin 56 on the end of the shaft of the form cylinder 16, see Fig. 2. From this construction it will 35 be evident that at each rotation of the form and impression cylinders the feed table 39 with the pile of sheets to be printed thereon will be given a single longitudinal movement back and forth in the swinging frame 31.

40 Journaled in the frame 31 is a feed roller 57 on one end of which is a pinion 58 that, through an idle pinion 59 turning on a stub-shaft projecting from the frame 31 and meshing with the gear wheel 23 on the impression cylinder 17, is rotated at the same superficial speed as the periphery of the impression cylinder, the two pinions 58 and 59 being of the same diameter. A second feed 45 roller 60 is carried in arms 61 on a rock shaft 62 and vibrates to and from the feed roller 57, the two being brought into engagement whenever a sheet is to be fed to the impression cylinder. The feed roller 60 may, if 50 desired, be mounted to remain always in contact with the roller 57 and yield only sufficiently to permit a sheet to pass therebetween and be fed thereby. It is preferred however to support the roller in the arms 61 as shown. Overlying a portion of the impression cylinder and projecting upwardly

in an inclined direction toward the feed roller 60 are one or more fixed guide fingers 63 that direct the edge of the sheet to be printed toward the impression cylinder, and between the same and the gripper fingers 25. 70 Above and slightly in advance of the feed roller 57 is a suction picker 64, in the present instance in the form of a hollow roller carried on a hollow shaft 65 in communication with a suitable suction device of any 75 desired type. Through the periphery of the roller 64 is a small opening 66 preferably formed in a disk of soft rubber 67 inserted in the roller. On one end of the roller shaft 65 is affixed a pinion 68 in engagement with a rack 69 fastened on the feed table 39, by means of which the suction roller is oscillated back and forth as the feed table reciprocates. The parts are so timed that at the beginning of the feeding movement of 80 the table 39 the rear side of the pile of sheets will be just beyond the center of the suction roller 64, as shown by the dotted line in Fig. 2, and the suction opening 66 will be slightly back from said side. As the table 85 39 begins to move, the rack 69 thereon turns the pinion 68 and the suction roller in the direction indicated by the arrow in Fig. 5. At the same time the suction through the 90 roller is opened. This draws the edge of the lowermost sheet of the pile away from the pile and carries it downward beneath a guide finger 70 toward the feed rollers 57, 60. After turning about a quarter revolution, the suction through the roller 64 is discontinued, thus releasing the edge of the sheet being fed, which edge continues its 95 downward movement, because of the reciprocation of the table 39 and the pile of sheets thereon, to the feed rollers 57, 60, the finger 70 serving to guide the edge of the sheet toward said rollers. As soon as the edge of the sheet enters between the feed rollers, the latter draws the sheet from the bottom of the pile and carries said edge toward the impression cylinder 17 and the gripper fingers 25 thereon. The table 39 advances in the direction of the feeding rollers a sufficient 100 distance to cause the edge of the sheet being fed to the press to be engaged by the rollers 57, 60, after which it returns to initial position, the same movement retracting the suction roller 64. As the table advances, the overhanging edge of the pile of sheets is supported and guided on the upper face of the finger 70 which is substantially in the plane of the upper face of the table. The finger 70 by which the sheets are directed toward the feed rollers comprises a relatively narrow plate 71 having a curved end 72 adjacent the suction roller 64. On the under surface of the plate 71 below the curved end 72 is a depending lug 73, the side adjacent the suction roller being inclined rearwardly 110 as at 74 and spaced from the suction roller 115 120 125 130

only sufficiently far to permit the sheet to pass freely therebetween. The finger 70 is adjustably supported on the underside of a cross-bar 75 extending between the forward ends of the side bars of the swinging frame 31, by bolts 76 that pass through slots 77 in the plate 71 and screwed into said cross-bar to hold the finger 70 in the desired position. On account of the fact that the upper face 10 of the finger 70 is in the plane of the upper face of the table, this face operates to guide the sheets on the table in a straight line and without forcing the sheets up or down.

When printing sheets made from paper ranging from the thinnest to moderately heavy material, the finger 70 is sufficient to insure the entrance of the sheet between the suction roller and the inclined surface 74, but when sheets of card-board and the like, 20 which are somewhat stiff and for this reason are liable to become disengaged from the suction roller through their resiliency, are to be fed, a plate 80 of thin sheet metal is adjustably and reversibly secured to the finger 70 for different grades of cardboard by screws 81 fastened through a slot 82 in the plate 80. The forward end of this plate is made quite narrow, as at 72^a, so that a thin and narrow point may be presented to the cardboard which projects a short distance beyond the curved end 72 of the finger in position to extend over the edge of each sheet the moment it is separated from the pile of sheets by the rotation of the suction disk 64, thus preventing the return of the sheet that is being fed to the pile should it become released from the suction roller by its resiliency. Plate 80 may be adjusted to bring its front end close up to suction roller 40 64 to adapt the finger to operate upon sheets of heavy material. The edge of the sheet being below the plate 80 the sheet will be carried by the movement of the feed table 39 to the feed rollers 57, 60. Upon loosening the bolts 76 the guide finger 70 may be adjusted to and from the suction picker with great accuracy by the thumb screw 83 threaded into the cross-bar 75 the enlarged head of said screw engaging a slot 84 in the outer end of the finger. By this means the thumb screw may be turned when the bolts 76 are loosened and the guiding finger 70 adjusted to suit the sheets that are to be fed to the press.

55 I provide take-up means between the rear edge of the table 39 and the suction picker to support the pile of sheets. For this purpose I prefer to fasten against the rear edge of the feed table 39 a plurality of tapes 85 which extend rearwardly from said table in parallel lines and around the hollow shaft 65 of the suction picker, or rollers on said shaft and from thence in a forward direction to rollers 86 on a cross shaft 87 the ends of which are mounted in

the side bars of the swinging frame 31. After passing around the roller 86 the tapes extend thence a short distance in a forward direction and are each connected to one end of a spiral spring 88, the other ends of the 70 springs being fastened to pins 89 that project from the bottom of the feed table. That portion of the tapes 85 between the table 39 and the suction picker 64 supports the rear of the pile of sheets that projects beyond said table in order to overlie the picker and prevents the sheets dropping between the table and picker. The tapes are taken up by being drawn around their guiding rollers as the table moves rearwardly, 80 and lengthen out on the reverse movement of said table. The function of the springs 88 is to maintain proper tension of the tapes and prevent them yielding to the weight of the pile of sheets when stretched. These 85 springs do not expand and contract as the table reciprocates as both ends of each tape are fastened to the table, one directly, and the other through the spring, there is therefore no variation in tension due to the movement of the table. 90

What is claimed as new is,—

1. In a printing press, the combination with a main frame, a form cylinder, an impression cylinder, and a take-off frame, arranged in parallel relation, a vertically swinging frame hinged to said main frame and overlying the impression cylinder and take-off, a reciprocating sheet supporting table on said swinging frame, automatic feeding mechanism delivering sheets to said cylinder carried by said swinging frame, and driving means supported on said main frame for actuating said automatic feeding mechanism, arranged to permit the free 100 swinging movement of said swinging frame without disconnecting said driving means. 95

2. In a printing press, the combination with a main frame, a form cylinder, an impression cylinder, and a take-off frame, arranged in parallel relation, a vertically swinging frame overlying the impression cylinder and take-off, a reciprocating table movable in said frame for supporting the pile of sheets to be printed, said pile overlying the rear edge of the table, automatic feeding mechanism delivering sheets to the impression cylinder carried by said swinging frame, and over which the overhanging portion of the pile of sheets projects, means 110 between said table and the feeding mechanism for supporting the overhanging portions of the pile of sheets, and driving means supported on said main frame for actuating said automatic feeding means, arranged to 115 permit the free swinging movement of said swinging frame without disconnecting said driving means. 120

3. In a printing press, the combination with an impression cylinder, an automatic 130

- sheet feeding mechanism delivering sheets to said cylinder comprising a pair of revolving feeding rollers, a reciprocating table for supporting a pile of sheets that project 5 rearwardly over said table, an oscillating suction picker operated by said table, a member coöperating with said suction picker for separating a sheet from the bottom of said pile and directing it toward said rollers, said member having a fixed flat upper face in the same plane with the upper face of the said table, and having an inclined face for guiding the sheet toward said rollers, and take-up means for supporting the 10 projecting portion of a pile of sheets.
4. In a printing press, the combination with an impression cylinder, an automatic sheet feeding mechanism delivering sheets to said cylinder comprising a pair of revolving feeding rollers, a reciprocating table for supporting the pile of sheets that project rearwardly over said table, an oscillating suction picker operated by said table, a member coöperating with said suction picker 15 for separating a sheet from the bottom of said pile and directing it toward said rollers, said member having a fixed flat upper face in the same plane with the upper face of the said table, and having an inclined face for 20 guiding the sheet toward said rollers, and take-up supporting means between the rear of the reciprocating table and the suction picker for supporting the projecting portion of said pile of sheets.
5. In a printing press, the combination with an impression cylinder, an automatic sheet feeding mechanism delivering sheets to said cylinder comprising a pair of revolving feeding rollers, a reciprocating table for 25 supporting a pile of sheets, a fixed guiding finger and an oscillating suction picker adjacent said finger and operated by said table to select a sheet from the pile of sheets and guided by said finger direct the same toward said feeding rollers, and a separating plate 30 adjustably attached to said finger and overlying the forward end of the same.
6. In a printing press, the combination with an impression cylinder, an automatic sheet feeding mechanism delivering sheets to said cylinder comprising a pair of revolving feeding rollers, a reciprocating table for 35 supporting a pile of sheets, a guiding finger and an oscillating suction picker adjacent said finger and operated by said table to select a sheet from the pile of sheets, and, guided by said finger direct the same toward said feeding rollers, and a separating plate 40 adjustably attached to said finger and formed with a narrow end projecting beyond said finger.
7. In a printing press, the combination with an impression cylinder, an automatic sheet feeding mechanism for delivering 45 sheets to said cylinder comprising a pair of revolving feed rollers, a reciprocating table for supporting a pile of sheets, an oscillating suction picker adjacent to and operated by said table to select a sheet from a pile of sheets on the table, a guiding finger arranged in the plane of the table and overhanging a portion of the suction picker, said finger having a downwardly inclined front wall, and a separating plate adjustably supported in a recess formed in the upper face 50 of said finger, said plate being adapted to have its forward end projected beyond the forward end of the finger.
8. In a printing press, the combination with a main frame, printing mechanism, a swinging frame, automatic feeding mechanism carried by said swinging frame including a reciprocating sheet supporting table, and means on said main frame for driving said automatic feeding mechanism and 55 arranged to permit the swinging movement of said swinging frame without disconnecting the said driving means.
9. In a printing press, the combination with an impression cylinder, an automatic sheet feeding mechanism delivering sheets to said cylinder comprising feed rollers, a reciprocating table for supporting a pile of sheets that project rearwardly over said table, an oscillating suction picker for drawing a sheet from the bottom of said pile and directing it toward said rollers, a cross-shaft below the table, a plurality of pulleys 60 mounted on said cross-shaft, and a plurality of flexible members passing around said pulleys and connected with said table, and also passing around said suction picker and attached to said table near the rear portion thereof so as to form a loop passing around said suction picker.
10. In a printing press, the combination with an impression cylinder, an automatic sheet feeding mechanism delivering sheets to said cylinder comprising a pair of revolving feed rollers, means for driving the said 65 feed rollers, a reciprocating table for supporting a pile of sheets that project rearwardly over said table, an oscillating suction picker for drawing a sheet from the bottom of said pile and directing it toward 70 said rollers, a plurality of tapes for supporting the projecting portion of the pile of sheets, a plurality of guide pulleys for said tapes under said table, said tapes passing in loops around said guide pulleys and 75 around said suction picker, the ends of said tapes being connected with said table.
11. In a printing press, the combination with an impression cylinder, an automatic sheet feeding mechanism delivering sheets to said cylinder comprising a pair of revolving feed rollers, means for driving the 80 said feed rollers, a reciprocating table for

supporting a pile of sheets that project rearwardly over said table, an oscillating suction picker operated by said table for drawing a sheet from the bottom of said pile and 5 directing it toward said rollers, a plurality of tapes for supporting the projecting portion of the pile of sheets, a plurality of guide pulleys for said tapes under said table, said tapes passing in loops around said guide 10 pulleys and around said suction picker, the ends of said tapes being connected with said table, said tapes having tension devices for maintaining the same taut.

12. In a printing press, the combination 15 with an impression cylinder of an automatic sheet feeding mechanism delivering sheets to said cylinder, comprising a pair of revolving feeding rollers, a reciprocating table for supporting a pile of sheets, a fixed 20 guiding finger and an oscillating suction picker adjacent said finger operating to draw a sheet from a pile of sheets, and guided by said finger to direct the same toward said feeding rollers, and a relatively 25 thin and narrow separating plate adjacent to said finger and overlying the forward end of the same.

13. In a printing press, the combination 30 with an impression cylinder of an automatic sheet feeding mechanism delivering sheets to said cylinder, comprising a pair of revolving feeding rollers, a reciprocating table for supporting a pile of sheets, a fixed guiding finger and an oscillating suction picker 35 adjacent said finger operating to draw a sheet from a pile of sheets, and guided by said finger to direct the same toward said feeding rollers, and a relatively thin and narrow separating plate removably attached

to said finger and overlying the forward 40 end of the same.

14. In a printing press, the combination with an impression cylinder of an automatic sheet feeding mechanism delivering sheets to said cylinder, comprising a pair of revolving feeding rollers, a reciprocating table for supporting a pile of sheets, a fixed 45 guiding finger and an oscillating suction picker adjacent said finger operating to draw a sheet from a pile of sheets, and 50 guided by said finger to direct the same toward said feeding rollers, said finger having a groove in the upper face thereof, and a separating plate secured in said groove and overlying the forward end of said guide finger, and projecting beyond the forward 55 edge of said guide finger.

15. In a printing press, the combination with an impression cylinder, an automatic sheet feeding mechanism delivering sheets 60 to said cylinder and comprising feeding rollers, a reciprocating table for supporting a pile of sheets, a fixed guiding finger and an oscillating suction picker adjacent said finger and operating to draw the lowest 65 sheet from the pile, and guided by said finger, to direct the same toward said feeding rollers, and a relatively thin and narrow plate projecting in advance of the forward edge of said guide finger. 70

In testimony whereof we have hereunto set our hands in presence of two subscribing witnesses.
